ATTORNEYS

UNITED STATES PATENT OFFICE.

FRANKLIN H. NEUBERGER, OF JEFFERSONVILLE, NEW YORK.

STATIONARY MORTAR-SPREADER.

1,130,532.

Specification of Letters Patent.

Patented Mar. 2, 1915.

Application filed September 5, 1912, Serial No. 718,608. Renewed December 31, 1914. Serial No. 879,960.

To all whom it may concern:

Be it known that I, FRANKLIN H. NEUBERGER, a citizen of the United States, and a resident of Jeffersonville, in the county of

5 Sullivan and State of New York, have invented a new and Improved Stationary Mortar-Spreader, of which the following is a full, clear, and exact description.

This invention relates to improvements 10 in mortar spreading devices, and has for an object to provide an improved structure in which mortar is adapted to be quickly and easily applied to concrete blocks and the like without wasting any of the mortar.

15 Another object of the invention is to provide a mortar spreader formed with raised side portions and a bottom having slots therein whereby mortar placed in the spreader and forced thereover will pass 20 through the slots to a desired point of discharge whereby the mortar will be distributed or placed at only the point where the same is needed.

A still further object of the invention is 25 to provide a spreading device for mortar which will direct or deposit the mortar on a concrete block or the like on the body of the block and will prevent any of the mortar from passing into the various openings or 30 holes formed in the block.

In carrying out the objects of the invention, a body portion is provided formed with raised sides and ends and with guiding lugs for holding the body portion properly 35 on the block when the device is in use. The bottom of the body portion is provided with slots designed to conform to the shape of the body portion of the concrete block on which the spreader is positioned so that the 40 mortar placed in the spreader may be forced through the slots on to the body of the block and thus avoid depositing any of the mortar in the holes in the block.

A practical embodiment of the invention 45 is represented in the accompanying drawings forming a part of this specification in which similar characters of reference indicate corresponding parts in all the views.

Figure 1 is a top plan view of an embodiment of the invention; Fig. 2 is a top plan view of a concrete block formed so as to receive the spreader shown in Fig. 1; Fig. 3 is a bottom plan view of the spreader shown in Fig. 1; Fig. 4 is an edge view of the 50 spreader shown in Fig. 1; and Fig. 5 is a

sectional view through the spreader taken approximately on the line 5—5 of Fig. 1, the same being shown applied to a concrete block.

Referring to the accompanying drawings 60 by numerals, 1 indicates the bottom of a spreader, and 2, 3, 4, and 5 represent the side and end flanges extending upwardly from the bottom 1. Any desired number of lugs 6 are provided on the bottom of the 65 spreader for correctly holding the spreader on the block, as shown in Fig. 5. The bottom 1 is provided with longitudinally arranged slots 7 and 8 for exposing the side walls 9 and 10 of a block 11 (Fig. 2). These 70 side walls are connected by suitable diagonal slots 12, 13, 14, and 15 which expose the various diagonally arranged walls 16 of the block 11. The walls of all of the slots are beveled from the upper surface to the lower 75 surface, as shown in Fig. 5 so as to spread the mortar passing through the slots over a larger area.

In operation when it is desired to lay a second block for instance on top of block 11, 80 the mortar spreader embodying the invention is placed on block 11 and a supply of mortar is deposited on the bottom 1 near the end wall 3 and is forced by a suitable trowel toward the end 5. As the mortar is 85 forced along the various slots are completely filled and the surplus mortar is allowed to remain upon the extension 17 after all of the slots have been filled. The spreader is then removed and the block being laid is placed on top of block 11 in the usual manner. It will be observed that the bottom 1 is provided with a plurality of 90 downwardly extending flanges 18 for giving a considerable depth to the slots so that an 95 appreciable amount of mortar is provided on the walls of block 11. When the second block is placed thereon the mortar naturally spreads out over the entire wall and provides a suitable packing and binding agent 100 for the two blocks. It will be noted that by using the spreader embodying the invention, comparatively wet or slushy mortar may be used and that little or none of the mortar is wasted by accidentally falling into 105 the holes of the block. The use of the wet or slushy mortar is very desirable as where the same is used the blocks need not be moistened before placing the mortar thereon as the blocks will absorb the moisture from 110

the wet or slushy mortar. It will be observed that the body portion 1 provides a solid portion over each of the holes in the block 11, and in order to secure together 5 these solid portions, connecting bars 19 are provided for each solid portion, though it will be of course evident that any desired number of these connecting bars may be used without departing from the spirit of 10 the invention.

Having thus described my invention I claim as new and desire to secure by Letters Patent:—

1. In a mortar spreader of the class described, a bottom formed with a plurality of spaced solid sections, connecting bars for connecting said sections so as to hold the same in correct positions, said connecting bars being of less thickness than the edges 15 of said sections, whereby mortar passing through the slots between said sections will pass beneath said connecting bars and make a continuous mortar bed, and an outside 20

body or frame connected with the end sections of said bottom.

2. In a mortar spreader of the class described, a bottom formed with a plurality of slots whereby the bottom is divided into solid sections, connecting bars for connecting said sections, an outside frame connected to the end sections of said bottom, said outside frame being formed with upwardly extending walls for preventing the spilling of mortar, and an end section arranged in line with said bottom for receiving the excess 35 mortar from said bottom, whereby said excess mortar will not be spilled when moving the spreader from one position to another.

In testimony whereof I have signed my name to this specification in the presence of 40 two subscribing witnesses.

FRANKLIN H. NEUBERGER.
